UNITED STATES PATENT OFFICE.

ALFRED CLEMENTS, OF PHILADELPHIA, PENNSYLVANIA.

DESIGN FOR A CARD MOUNT OR MAT.

SPECIFICATION forming part of Design No. 32,803, dated June 5, 1900.

Application filed April 27, 1900. Serial No. 14,628. Term of patent 14 years.

To all whom it may concern:

Be it known that I, ALFRED CLEMENTS, a citizen of the United States, residing in Philadelphia, Pennsylvania, have invented a certain new and original Design for a Card Mount or Mat, of which the following is a specification.

My design for a card mount or mat is fully illustrated in the accompanying drawing, which represents a face view of the mount or mat.

The essential feature of the design is the gradual tinting of the mount or mat from a light tint at the edge to a dark tint at or near the center, surrounding the picture.

The tint of the mount or mat is graded, being light at the edge *c* and gradually shading to a dark shade at the center *d*, giving the peculiar effect shown in the drawing.

I claim—

The design for a card mount or mat, as herein described and as illustrated in the accompanying drawing.

In testimony whereof I have signed my name to this specification in the presence of two subscribing witnesses.

ALFRED CLEMENTS.

Witnesses:

WILL. A. BARR,
JOS. H. KLEIN.
